UNITED STATES PATENT OFFICE.

GEORGE A. SPARKS AND VERNON C. SPARKS, OF LODI, CALIFORNIA, ASSIGNEES TO
S & G MANUFACTURING COMPANY, OF STOCKTON, CALIFORNIA.

WATER CIRCULATOR FOR INTERNAL-COMBUSTION ENGINES.

Application filed December 29, 1920. Serial No. 433,791.

To all whom it may concern:

Be it known that we, GEORGE A. SPARKS and VERNON C. SPARKS, citizens of the United States, residing at Lodi, in the county of San Joaquin, State of California, have invented certain new and useful Improvements in Water Circulators for Internal-Combustion Engines; and we do declare the following to be a full, clear, and exact 10 description of the same, reference being had to the accompanying drawings, and to the characters of reference marked thereon, which form a part of this application.

This invention relates to improvements in devices for circulating the water in the cooling systems of internal combustion engines, being especially intended to be used on engines which are not equipped with pumps and depend on the thermo-siphon principle 20 of water circulating.

The principal object of our invention is to provide an impeller device which will positively circulate the water, and raise it to a considerable height; and which will 25 take the form of an attachment which replaces one of the standard pieces of equipment on some engines, such as the Ford, and for which we have illustrated the device in this application. We have also arranged to run the device from the fan belt or pulley as regularly equipped without disturbing the latter in any way.

Another object is therefore gained and accomplished by such a structure, this being the provision of a power operated unit 35 which does not necessitate dismantling and rebuilding the engine to accommodate the same, as is unfortunately true of a great many devices, admirable in themselves, but which are precluded from being in general use on account of this fact.

Our device however may be installed on an engine already built, in but a very few minutes, which feature alone should appeal 45 to prospective users, who are naturally dubious to try out any devices which necessitate alterations being made on their engines.

A further object of the invention is to produce a simple and inexpensive device and 50 yet one which will be exceedingly effective for the purposes which it is designed.

These objects we accomplish by means of such structure and relative arrangement of parts as will fully appear by a perusal of the 55 following specification and claims.

In the drawings similar characters of reference indicate corresponding parts in the several views.

Fig. 1 is a fragmentary outline of the front end of a motor-car engine, showing our improved device installed thereon.

Fig. 2 is an enlarged view of the device partly in section.

Fig. 3 is an end elevation thereof.

Fig. 4 is a sectional view of a modified form of the device.

Referring now more particularly to the characters of reference on the drawings, the numeral 1 denotes the engine proper, having the usual water outlet manifold 2, leading to the radiator and the cooling fan 3 driven by a belt 4 from a pulley 5 on the crank shaft 6.

The manifold 2 on the Ford and other engines, terminates at the forward end of the cylinder casting, and has a separate elbow secured thereto, which elbow projects upwardly and is connected to a rubber hose 7 which leads to the radiator (not shown).

This elbow we remove, and replace it with another elbow 8 of the same general shape and size, but provided with a horizontal bearing boss 9 in central alinement with the opening of said elbow into the manifold 2.

Journaled in the boss 9 and also in an outer and spaced boss 10 supported by a bracket 11 formed integral with the elbow 8

is a shaft 12, held against longitudinal movement, on the end of which inside the elbow are secured impellers 13. There are preferably a pair of such impellers, which are in the form of the usual screw type of propeller, and may, for cheapness and ease of manufacture be cut or stamped from sheet metal and held in spaced relation on the shaft 12 by means of collars 14, and clamped in place by a nut 15. The corresponding blades of these impellers are substantially parallel to each other, but are preferably arranged in staggered relation, the result being that water drawn in by the one nearest the member 2 is thrown against the blades of the inner impeller member and by them diverted upwardly.

By this means we are able to raise the water, or keep the same in rapid circulation, in a much more efficient manner than would be possible with a single impeller, and thus maintain a very cool motor at all times.

The outer end of the boss 9 is provided

with a packing gland 16 and with a packing nut 17 while a grease cup 18 is positioned on the outside and communicates with the bearing surface of the boss 9.

5 On the shaft 12 between the two bearings thereof is a pulley 19, preferably of the same type as the pulley 5, and which is slideable on the shaft within the limits of the bearings, being provided however with a set 10 screw 20 so that it may be clamped in position.

By making this pulley hollow and open at one end, it may normally surround the nut 17 so as to bring it in vertical alinement 15 with the pulley 5, while at the same time it may be unclamped and slid along the shaft so as to allow a wrench to be applied to the nut 17 when occasion demands.

To drive the pulley 19, a belt 21 passes 20 around the same and also around the pulley 5 on the outside of the belt 6, so that there will be a good grip on the belt 21 without great strain or wear on the same, and without disturbing the original fan-drive in any 25 manner.

In Fig. 4 another form of impeller is shown, having the form of a small centrifugal pump.

In this case the water outlet member is 20 of special shape as at 22, while the impeller 23 is of the usual centrifugal-pump vane form, being set in some distance from the line of connection with the manifold 2, and discharging into a spiral outlet 24 which 25 is shaped at its upper end to receive the hose 7 thereover.

The pulley 19^a of this type is driven from the pulley 5 in the same manner as the first described style.

40 In either case, the operation, which is self evident, will be the same, and the installation of the device is a matter of minutes, without necessitating any structural changes being made to the engine, or the 45 securing thereto of any parts requiring new holes, pads or other attachments being placed on the engine.

Although we have particularly described 50 our device as being interposed in the cooling system adjacent the top or hottest part thereof, it will of course work equally well if interposed near the lowest or at any other intermediate point.

From the foregoing description it will 55 be readily seen that we have produced such a device as substantially fulfills the objects of the invention as set forth herein.

While this specification sets forth in detail the present and preferred construction 60 of the device, still in practice such deviations from such detail may be resorted to as do not form a departure from the spirit of the invention, as defined by the appended claims.

Having thus described our invention, what we claim as new and useful and desire to 65 secure by Letters Patent is:—

1. A device of the character described comprising a hollow fitting adapted to be interposed in the water circulation line of a gas engine, said fitting having a horizontal 70 inlet and a substantially vertical outlet, and a pair of driven and spaced impellers of the blade type mounted in the fitting, one of said impellers being adjacent the intake and the other substantially in central alinement with the vertical outlet, the blades of one being staggered relative to the blades of the other, whereby the water is drawn through the intake by the adjacent impeller, and is then thrown against the blades of the 80 other, to be diverted upwardly by the latter. 75

2. A water pump comprising a hollow open ended casing having a horizontal intake and a substantially vertical outlet, a shaft journaled in the casing and projecting 85 toward the intake, and double impeller means on the shaft arranged to draw the water horizontally through the intake and throw it directly through the outlet without interference with the walls of the casing. 90

3. A water pump comprising a hollow open ended casing having a horizontal intake and a substantially vertical outlet, a shaft journaled in the casing and projecting toward the intake, and a pair of blade impellers mounted in closely spaced relation 95 on the shaft; one impeller being located adjacent but inwardly of the intake and arranged to draw the water horizontally therethrough and the other being substantially in central alinement with the outlet and arranged to catch the water from the other impeller and divert it directly toward the outlet. 100

4. A water pump comprising a hollow open ended casing having a horizontal intake and a substantially vertical outlet, a shaft journaled in the casing and projecting toward the intake, and a pair of blade impellers mounted in closely spaced relation 105 of the shaft; one impeller being located adjacent but inwardly of the intake and arranged to draw the water horizontally therethrough and the other being substantially in central alinement with the outlet and arranged to catch the water from the other impeller and divert it directly toward the outlet, and a bearing member for the shaft 110 formed with and projecting into the casing and against which the inner impeller abuts to maintain it in proper alinement with the outlet. 115

In testimony whereof we have affixed our signatures.

GEORGE A. SPARKS,
VERNON C. SPARKS.
